UNITED STATES PATENT OFFICE

2,211,042

APPARATUS FOR AND METHOD OF RE-FORMING THE UPERS OF SHOES

Adolf H. Altvater, University City, Mo., assignor to Milton L. Dodge, Newburyport, Mass.

Application January 24, 1936, Serial No. 60,612

11 Claims. (Cl. 12—51)

The present invention relates to machines which are used in the manufacture and repair of shoes to press the uppers of finished shoes.

The present invention presents an improvement on the re-forming machines disclosed in my Patents Nos. 2,164,861 and 2,164,862. As explained in these patents when a shoe, such as a woman's pump, is pulled from a shoe-making last, the strains to which the shoe is subjected cause irregularities in the skirtings along the straight runs of the top edge of the shoe, spread the skirtings outwardly so that the interior linings at the sides of the shoe are unduly exposed, and generally rob the shoe of the trim appearance intended by its designer and sought after during the various shoe-making operations. It should also be pointed out that a certain amount of this distortion results from the mere trying on of shoes in retail stores. The re-forming machines disclosed in my said patents and disclosed herein are designed to restore to shoes their trim appearance.

The re-forming machines disclosed in my said patents are designed for use primarily upon women's pumps. But the strains of last-pulling affect shoes of the Oxford and blucher types much as they affect pumps, and render it just as desirable that the trim appearance of the shoes be restored. Inasmuch as shoes of the Oxford and blucher types have closure wings not found in pumps, and the tops of these wings extend well above the level of the other portions of the top edge at the sides of the shoe, the machines disclosed in my said patents are not adapted for re-forming shoes of the blucher or Oxford types.

It is accordingly the principal object of the present invention to provide a re-forming machine which, in addition to re-forming the skirtings of the top edge along the sides of shoes generally, will also re-form the closure wings of shoes of the blucher or Oxford types.

Re-forming machines have been provided chiefly for women's shoes since the materials of which they are made are generally lighter than in the case of men's shoes, and are more affected by the strains of shoe-making operations or by the trying on of shoes in retail stores. There is, however, a certain amount of distortion of men's blucher and Oxford shoes resulting from shoe-making operations or from trying on, and it is just as desirable that these shoes be re-formed to restore their intended appearance. As men's shoes of these types also have closure wings, which the machines disclosed in my said patents are not adapted to re-form, it is a further object

of the present invention to provide a machine for re-forming men's blucher and Oxford shoes.

To the accomplishment of these objects and such others as may hereinafter appear, the various features of the present invention reside in certain devices, combinations, and arrangements of parts fully set forth hereinafter and then pointed out in the appended claims, possessing advantages which will be readily apparent to those skilled in the art.

The various features of the present invention will be readily understood from an inspection of the accompanying drawings, illustrating the best form of the invention at present known to the inventor, in which,

Figure 1 is a view in left side elevation of the re-forming machine;

Fig. 2 is a view in perspective of one of the outside shaping forms;

Fig. 3 is a view taken along the line 3—3 of Fig. 4;

Fig. 4 is a detail view in left side elevation, partially in section, the swinging arm being removed to show underlying parts;

Fig. 5 is a view in plan of a woman's blucher shoe as it appears after being re-formed;

Fig. 6 is a detail view in left side elevation showing a modified inside shaping form; and

Fig. 7 is a view in sectional plan of an alternative construction for the outside shaping forms.

For the purpose of disclosure, the shoe 10 operated upon by the re-forming machine shown in Figs. 1 and 4, is illustrated and described as a woman's low-cut shoe of the blucher type (Fig. 5), the top edge 11 around the opening of which is bound with French cord and comprises a curvature 12 at the rear and side runs 13 and 14 on opposite sides of the shoe, respectively. The top edge also extends along the closure wings 15 and 16 at the front of the shoe, which is provided with a tongue 17. These wings 15 and 16 extend well above or beyond the level of the side runs 13 and 14, respectively. As is well known to those skilled in the art, the upper 18 and the lining 19 (Fig. 3) of a blucher shoe are secured together by various seams, one of which comprises the top seam 20 (Fig. 3) lying close to and running along the top edge 11. For convenience herein, the inner and outer surfaces of the shoe 10 lying adjacent and running along the top edge 11 are each designated as "the skirting," and the upper 18 and the lining 19 will be together referred to hereinafter as the "upper." At the rear of the shoe the upper is closed by a back seam exposing to view a back

seam crease 21 (Fig. 5) which is not completely shown in the figure.

The blucher shoe illustrated in Fig. 5 represents a shoe after it has been operated upon by the re-forming machine, and shows the desirable appearance of the top edge 11 and the wings 15 and 16 intended by the designer and sought to be attained throughout the various shoe-making operations. The distortion of the skirtings along the top edge 11 resulting from last pulling, for example, or from trying the shoe on as in a retail store, has been removed, and the original appearance of the shoe has been restored.

The embodiment of the present invention illustrated in Figs. 1, 2, 3, and 4 utilizes to a great extent the machine structure disclosed in my Patents No. 2,164,861 and No. 2,164,862, particularly the latter. For this reason those machine elements which are not new with the illustrated embodiment of the present invention will be referred to only generally.

Referring to Figs. 1 and 4, the re-forming machine comprises a head 22 provided with a forwardly extending and vertically arranged arm 23 the front end of which is provided with a shaping mold 24 adapted to fit within and support a shoe. Mounted on a vertical axis at each side of the arm 23 is a swinging arm, the left hand swinging arm 25 being shown in Figs. 3 and 4, and the right hand swinging arm 26 being shown in Fig. 1. At their free ends the swinging arms 25 and 26 carry flat plates 27 (Fig. 3) and 28 (Fig. 1), respectively, on which are readily and detachably mounted outside shaping forms 30 and 29, respectively. As will be more fully described later, the inside mold 24 and the outside forms 29 and 30 have substantially complementary surfaces which cooperate to press the shoe upper from opposite sides thereof simultaneously to re-form it.

In order to move the swinging arms 25 and 26 towards and away from the arm 23, and thereby move the outside shaping forms 29 and 30 towards and away from the inside shaping mold 24, the arms 23, 25, and 26 receive loosely a horizontal bolt 31 the opposite ends of which are received by the yoked arms of an operating lever 32. A spring 33 (Fig. 4) coiled about the bolt 31 and having its ends engaging the swinging arms 25 and 26 maintains these arms normally spread apart so that the mold 24 is readily accessible for mounting a shoe thereon. Studs 34 and 35 carried by the arms of the lever 31 limit the outward swing of the swinging arms 25 and 26 and cooperate with wedge blocks 36 and 37 carried by the swinging arms, respectively, to press the arms towards the arm 23 and lock them there when the operating lever 32 is moved forwardly (to the left, viewing Fig. 3).

Referring to Figs. 1, 3, and 4, the inside shaping mold 24 is similar to the inside shaping molds described in my said patents, and is elongated and provided with operative convex shaping surfaces 38 of uniform curvature on its opposite lateral sides. The mold 24 is arranged vertically so that a shoe 10 may be mounted upon it with the toe thereof pointing downwardly and with the heel portion of the upper being supported by the convex top 39 of the mold. A stop 40 (Figs. 1 and 4) limits the extent to which the heel end of the shoe fits over the top 39. The mold 24 is provided in front with a cavity 41 in which a heating unit cartridge 42 may be placed and connected by wiring 43 to a source of electricity (not shown). A plate 44 covers the cavity 41. In order to

permit the mold 24 to enter the shoe readily, the bottom of the mold is provided with a downwardly and rearwardly extending nose 45.

The above is a general description of the structure and mode of operation of those parts of the illustrated embodiment of the present invention which are described in detail and claimed in my said patents, this description being given so that the following description of the features constituting my improvements may be more readily understood.

The operative shaping surfaces 38 of the mold 24 are adapted by reason of their construction to engage the skirtings adjacent the top edge along the side runs of the shoe as indicated in Fig. 4. It will be apparent, however, that since the wings 15 and 16 of the shoe extend well above the level of the top edge of the side runs 13 and 14, respectively, the operating shaping surfaces 38 of the mold 24 are not adapted to engage these wings.

To achieve wing engagement, associated with the opposite sides of the mold 24 are vertical plates 46 and 47 (Figs. 1, 3, and 4) which abut the mold 24 and extend rearwardly and are secured at their tops to the stationary arm 23 by means of screws 48. Referring particularly to Fig. 3, the mold-abutting edge 49 of the plate 47 is curved slightly outwardly as indicated at 50, and on its inner face is beveled, as indicated at 51. With this construction the beveled portion 51 lies against the curvature of the mold 24 and by reason of the curve 50 the edge 49 lies close to a surface 38 of the mold so that the outer surface 52 of the plate 47 comprises substantially a continuation of its associated mold surface. The plate 46 is formed in a manner corresponding to the plate 47, and is similarly mounted. Referring to Figs. 1, 3 and 4, it will be seen that the plates 46 and 47 are associated with the mold 24 in such position along its length as to register with substantially the entire inner surface of the shoe wings, and are larger than the wings to insure this result.

With the above described construction it will be seen that the operative shaping surfaces 38 of the mold and the surfaces 52 of the plates 46 and 47 comprise together a shaping form adapted to engage the skirtings along the top edge of the side runs 13 and 14 of the shoe and also engage the wings 15 and 16 of the shoe so that under the influence of a suitable pressing means these engaged portions of the shoe are shaped and given a desired appearance.

This shaping is effected by the outside shaping forms 29 and 30, of corresponding construction, and the operating mechanism therefor described above. The outside shaping form 30 comprises a base portion 53 (Fig. 2) and a wing portion 54 extending therefrom. The base portion 53 is similar to the outside shaping form disclosed in my Patent No. 2,164,862, and is preferably made of solid rubber. In order that they may coact with the operative shaping surfaces 38 of the mold 24, the operative shaping surfaces of the base portions of the forms 29 and 30 are concave and are of a uniform curvature complementary to the curvature of the shaping surfaces 38. Embedded in the rear face of the rubber base portion 53 are studs 55 by which the form may be removably secured to the plate 28 (Fig. 1) in the manner disclosed in my said Patent No. 2,164,862. The operative shaping face of each base portion is preferably formed by a molding operation, the rubber material of the

form lending itself well to molding from both a point of accuracy and a point of cheapness of manufacture.

The wing 54 extending from the base portion 53 is flat and relatively thin, is large enough to engage substantially the entire surface of the closure wing of the shoe, and extends from the lower portion of the base 53 to effect this result. The operative shaping contour of the base portion 53 and the shaping face of the wing 54 are preferably covered by some material 56 other than rubber, such as leather vulcanized into the rubber or adhesively secured thereto.

Viewing Figs. 1 and 3, it will be seen that when the swinging arms 25 and 26 are pressed towards the arm 23 by operation of the lever 32, the base portions of the forms 29 and 30 are pressed against the opposite side runs 13 and 14, respectively, of the shoe which in turn are pressed against the shaping surfaces 38 of the mold 24. In order to press the wing 54 of the form 30 against the wing 16 of the shoe, the swinging arm 25 is provided with a block 57 (Fig. 3) adapted to engage the outer face of the wing 54. The swinging arm 26 is provided with a block 58 (Fig. 1) corresponding to the block 57 and functioning to press the wing of the form 29 against the wing 15 of the shoe.

The outside forms 29 and 30 have been described and illustrated as comprising base portions provided with integral wings. While this construction is easy to manufacture since the rubber can be poured into a suitable mold in one operation, from a shoe manufacturer's point of view it is preferable that the wings be more resilient than the base portions, and this is most easily effected if the wings are separate pieces from the base portions, being either vulcanized therewith or adhesively secured thereto. The purpose of this construction lies in handling the outside forms, that is, in mounting and dismounting them and in storage. Were the wings integral with the base portions, there might be a tendency for the wings to crack or break away from the base portions in repeated handling by reason of their stiffness and relative thinness. A wing more resilient than the base portion will flex readily and therefore stand up longer under repeated handling.

Such a construction for the outside forms is indicated in Fig. 7. The base portion 59 is formed of solid rubber in a manner corresponding to the base portion 53 (Fig. 3), and the wing 60, also preferably of rubber such as fine sponge, is more resilient than the base portion 59. The forward edge portion of the wing 60 is beveled on its outer face to engage and be secured to a corresponding beveled surface on the base portion 59, and the forward edge portion of the wing 60 is shaped on its inner face so as to merge with and form a continuation of the contour of the shaping face of the base portion. The base portion 59 and the wing 60 are provided with a shoe contacting surface 61 of different material as is the case of the forms shown in Figs. 2 and 3. When completed, the outside forms made as shown in Fig. 7 have the same over-all shape as the outside forms 29 and 30 and are operated by the machine in the same manner.

In my Patent No. 2,164,862, it was pointed out that if a woman's shoe is allowed to hang freely on the mold and be supported by only its heel end, it sometimes happens that the vamp buckles or crimps as the result of moving the outside shaping forms against the freely hanging

shoe. To prevent possible injury to the vamp from this cause, in my said patent I disclosed a construction for holding the vamp against buckling or crimping during the application of pressure. This construction also served to position the shoe on the inside mold so that the skirtings adjacent the top edge along the side runs of the shoe were held in substantial conformity to the operative shaping surfaces of the inside mold prior to the application of pressure by the outside forms.

I have utilized the basic features of this construction in the illustrated embodiment of the present invention, making certain desirable improvements thereon. Referring to Figs. 1 and 4, an arm 62 is pivoted at one end to the head 22 and extends forward under the arm 23 to a point near the mold 24. Pivoted to the free end of the arm 62 is a bent strip 63 comprising a forwardly extending short arm 64 and a longer arm 65 bent downwardly and rearwardly of the arm 64. The free end of the arm 65 is provided with a block 66 adapted to be inserted in the toe portion of the shoe, as shown in Fig. 4, and the arm 65 is of such length as to clear the opening of the shoe at the base of the tongue 17. A leaf spring 67 yieldingly resists upward movement of the bent strip 63 on the arm 62, and the arm 62 is pulled downwardly by a coil spring 68 connected to the head 22. A U-shaped clip 69 resting on a run of the arm 23 limits the downward movement of the arm 62.

Except for certain improvements, presently to be described, the above construction is disclosed in my Patent No. 2,164,862. The shoe is positioned in the machine first by inserting the block 66 into the toe and then pulling the shoe up against the tension of the spring 68 to cause the nose 45 to enter the shoe. The shoe is then pulled further upward against the tension of the spring 68 and the heel end of the shoe is pushed along the top 39 of the mold 24 so as to rest on it in abutment with the stop 40. In this operation the tongue 17 may be either tucked into the shoe or it may extend outwardly.

In this construction shown in my said Patent No. 2,164,862, the rear of the nose of the mold was smooth and an arm similar to the arm 65 rested against it when the shoe was mounted in the machine. The arm was of appreciable thickness and was concavo-convex, both for stiffening purposes and so as to conform to the curvature of the rear of the mold. While this construction served to hold the shoe as a whole taut and hold the skirtings in substantial conformity to the operative shaping surfaces of the inside mold, the thickness of the material of the arm similar to the arm 65 necessarily caused the vamp to be spaced along and adjacent its longitudinal center from the rear of the mold, and this to a certain extent caused the contour of the upper, in its condition of tautness, to vary slightly from the shaping contour of the mold. In some cases it was found that in re-forming the upper this differential of contour affected the re-formation of the shoe adversely in that the arm slightly distorted portions of the vamp away from the adjacent portions pressed by the forms.

To obviate such a possibility, in the illustrated embodiment of the present invention the rear of the nose 45 is not smooth, but is provided with a recess 70 (Fig. 4) wide enough to receive the arm 65 of the bent strip 63 and deep enough so that the arm 65 lies appreciably within the mouth of the recess. The arm 62 is, of course,

made sufficiently long to achieve this result, or the arm 64 may be made sufficiently long for this purpose. With this construction the arm 65 is spaced from the vamp of the shoe so that the inner surface of the taut upper adjacent the nose 45 engages the mold and necessarily conforms to its shaping contour.

Broadly considered it will be seen that the stationary mold 24, the plates 46 and 47, the arm 62, and the block 66 constitute an inside shaping form which is normally maintained fully extended by the spring 68 but which is contracted by the act of inserting the inside shaping form into the shoe. When the inside shaping form is within the shoe the springs 67 and 68 hold the mold top 39 and the block 66 firmly against the rear and toe ends of the shoe, respectively, and also serve to draw the wings of the shoe into engagement with the plates 46 and 47 and the skirtings of the side runs along the top edge of the shoe into engagement with the operative shaping surfaces 38 of the mold 24.

In Fig. 6 there is shown a modified inside shaping form adapted for use in re-forming men's blucher or Oxford shoes. This modified form comprises an elongated shaping mold 71 mounted vertically like the mold 24 upon a stationary arm 72 similar to the stationary arm 23. The mold 71 is provided on its opposite lateral sides with convex operative shaping surfaces of uniform curvature and with a convex top 73. Features of construction presently to be described render it unnecessary that the mold 71 have a nose like the nose 45, and the length of the mold 35 is accordingly such that the mold extends from the heel of the shoe 74 (shown as an Oxford for purposes of disclosure) to a point slightly beyond the top of the lacing fly. The mold 71 is deep enough so that its operating shaping 40 surfaces may engage not only the skirtings adjacent the top edge of the shoe but also the top portions of the closure wings, as indicated.

The arm 72 differs from the arm 23 only at its forward end, and is thus replaceable on the head 22 as a substitute for the arm 23. This substitution requires no other change in the machine except the removal of the outside shaping forms 29 and 30 and their replacement with other shaping forms having concave shaping 50 surfaces complementary with the shaping surfaces of the mold 71 and adapted to coat therewith to re-form the upper. The general mode of operation of the machine thus arranged is the same as that of the machine shown in Figs. 1 55 and 4 and in either of my said pending applications.

The materials used in men's shoes being generally heavier than the materials used in women's shoes, there is less danger in the case of the former of a buckling or crimping of the upper when the outside shaping forms are brought into pressing position. It is therefore not necessary that the upper of a man's shoe be held as taut as is the case with women's shoes, and for this reason in utilizing the present invention upon men's shoes, the construction exemplified by the arms 62 and 65, the block 66, and the spring 68 may be dispensed with. It is, however, desirable that a man's shoe be slightly taut while being re-formed.

To this end the top of the arm 72 is provided with a stop 75 for engaging the heel end of the upper, and is also provided forwardly with a depending lug 76 adjacent the rear of the base 75 of the mold 71. Projecting forwardly from the

lug 76 for a short distance under the mold 71 is a rod 77 which is bent downwardly at approximately 45 degrees at a point lying below the front of the mold 71. At its forward end the bent rod 77 is provided with a portion 78 of reduced diameter which extends loosely into a passage 79 formed in a cylindrical head 80 and provided with a blind end. The end 81 of the reduced portion 78 is slightly enlarged so as to fit the passage 79 formed in the head 80. In manufacture a coil spring 82 is interposed between the blind end of the passage 79 and the enlarged end 81 of the reduced portion 78, after which the open end of the passage 79 is pinched so as to lie close to the reduced portion 78 and prevent the head 80 from leaving the passage. This construction thus provides a resilient plunger extending forwardly and downwardly from the mold 71, the plunger being capable of movement for a distance equal to the extent that the reduced portion 78 is exposed.

As shown in Fig. 6 the head 80 of the plunger engages the insole of the shoe substantially at its ball line when it is mounted on the mold 71, thus serving to limit initially the extent to which the mold enters the shoe. The head 80 also serves to facilitate the entrance of the mold 71 into the shoe, thus functioning like the nose 45, and may be utilized to lift the tongue 83 of the shoe out of the way for the ready insertion of the 30 mold.

It will be seen that the mold 71, the rod 77, and the head 80 together comprise an inside shaping form for engaging the skirtings adjacent the top edge along the side runs of the shoe and also the top portions of the wings formed by the lacing fly. The shoe is mounted on the form by first utilizing the head 80 to pull out the tongue 83 and then as a guide for the entrance of the bottom of the mold 71 into the shoe. The shoe 40 is then pulled upwardly and over the mold until its heel portion is supported by the mold top 73 and engages the stop 75. In this position, the plunger head 80 engages the insole of the shoe. Should it be desired to subject the upper to heat 45 as well as pressure, the mold 71 may be provided with a heating cartridge unit 84 and connected wiring 85 in a manner similar to this provision for the mold 24.

While the head 80, pressed outwardly by the 50 spring 82, abuts the insole of the shoe substantially at its ball line, it is not intended that the outside shaping forms should engage the shoe while it rests merely by gravity upon the mold top 73 and against the head 80. Prior to bringing 55 the outside shaping forms into pressing position, but after the shoe is mounted in the machine, the operative presses on the outsole against the tension of the spring 82, thereby causing the head 80, while still engaged with the shoe, to 60 move rearwardly along the reduced portion 78. Thereupon, with the shoe held in this position by the operative, the outside shaping forms are placed in pressing position, and the operative 65 then releases his pressure on the shoe. With this mode of operation, the shoe is actually clamped in the machine by reason of its engagement with the inside and outside shaping forms, but since these forms do not engage the entire shoe, the pressure of the spring-pressed head 70 80 against the insole of the shoe operating in a direction away from the mold 71 eliminates any slack there may be in the vamp and serves to hold it under a slight tension during the re-forming operation. This feature is particularly 75

useful in retail stores where it is customary in preparing men's shoes for trying-on for the salesman to bend the toe portion of the shoe back and forth, thus causing the vamp, back of the tip, to wrinkle. The shoe thus wrinkled loses its trim appearance, and if the shoe is not sold the wrinkles create sales resistance when subsequently presented to another prospective customer. By moistening the inside of the toe portion opposite the wrinkling with a damp cloth or sponge, the try-on wrinkles may be eradicated through the use of the embodiment of the invention illustrated in Fig. 6 as the heat generated in the cartridge unit 84 acts to dry or tree the shoe while it is held with the moistened vamp in a slightly stretched condition.

The extent to which the operative moves the head 80 in initially holding the shoe in the machine depends upon the nature of the shoe, but the reduced portion 78 may be made long enough to accommodate all sizes in a given series, or there may be provided different sized units each comprising a rod 77, reduced portion 78, head 80, and spring 82.

Nothing herein explained is to be interpreted as limiting the present invention in the scope of its application to use in connection with the particular apparatus or the particular mode of operation or both selected for purposes of illustration and explanation. The present invention is not limited to the illustrated and described details of construction, nor is it limited to the conjoint use of all its features, nor is it to be understood that these particulars are essential since they and the steps of the method disclosed may be modified within the skill of the artisan without departing from the true scope of the actual invention, characterizing features of which are set forth in the following claims by the intentional use of generic terms and expressions inclusive of various modifications.

What is claimed as new is:

1. In a re-forming machine, the combination with an inside shaping form and outside shaping forms to press at least the skirtings along the top edge on the opposite sides of a shoe against the shaping contour of the inside form, of means for holding the vamp adjacent its longitudinal center line in engagement with the shaping contour of the inside form during the pressing operation.
2. In a re-forming machine, coacting inside and outside shaping forms for pressing portions of the upper of a shoe from opposite sides simultaneously, the inside form comprising a stationary mold engaged with the rear end of the shoe, a part engaged with the toe end of the shoe, and a support for the second named part extending under the vamp generally along the longitudinal center line thereof and spaced therefrom.
3. In a re-forming machine, coacting inside and outside shaping forms for pressing portions of the upper of a shoe from opposite sides simultaneously, the inside shaping form comprising a stationary mold engaged with the rear end of the shoe and provided with a recess, a block engaged with the toe end of the shoe, and a supporting arm for the block, said arm being received by the recess and supported outside the shoe.
4. In a re-forming machine, coacting inside and outside shaping forms having substantially complementary surfaces for pressing portions of the upper of a shoe from opposite sides simul-

taneously, the inside form comprising a stationary mold and means associated therewith tending to urge the shoe away from the mold while being pressed thereagainst by the outside forms.

5. In a machine for re-forming a shoe provided with closure wings, coacting inside and outside shaping forms having substantially complementary surfaces for pressing the wings and the skirtings of the top edge at the side runs of the shoe from opposite sides simultaneously, and means for tensioning the vamp of the shoe while the wings and skirtings are being pressed.

6. In a re-forming machine, coacting inside and outside shaping forms having substantially complementary surfaces for contacting the inner and outer surfaces of the upper of a shoe, the inside shaping form comprising a stationary mold engageable with the rear end of the shoe, a stationary arm, and means movable on the arm for engaging an interior surface of the shoe.

7. In a re-forming machine, coacting inside and outside shaping forms having substantially complementary surfaces for contacting the inner and outer surfaces of the upper of a shoe, the inside shaping form comprising a stationary mold engageable with the rear end of the shoe, a stationary arm, a member movable thereon for engaging an interior surface of the shoe, and means offering a yielding resistance to the movement of said member.

8. In a re-forming machine, coacting inside and outside shaping forms having substantially complementary surfaces for contacting the inner and outer surfaces of the upper of a shoe, the inside shaping form comprising a stationary mold engageable with the rear end of the shoe and a resiliently extensible member comprising a stationary part and a movable part engageable with an interior surface of the shoe.

9. That improvement in the art of removing try-on wrinkles from an area on the exposed face of the vamp of a shoe adjacent the tip which consists in moistening the unexposed face of the vamp opposite the wrinkled area, clamping the shoe at a point spaced from the moistened area, and subjecting the moistened area of the clamped shoe to the influence of heat and tension.

10. In a machine for re-forming shoes provided with closure wings, the combination with an inside shaping form having a shaping contour for engagement with the side portions of the upper adjacent to the shoe opening and a wing thereof, of an outer pressing form having parts for engagement with the outer face of the shoe adjacent to the shoe opening and with one of said wings, and means directly engaging one of said parts and yieldingly connected to the other part for pressing said outer form toward said inside form.

11. In a machine for re-forming shoes provided with closure wings, the combination with an inside shaping form having a shaping contour for engagement with the side portions of the upper adjacent to the shoe opening and a wing thereof, of an outer pressing form having parts for engagement with the outer face of the shoe adjacent to the shoe opening and with one of said wings, and means directly engaging said wing-engaging part and yieldingly connected to the other part for pressing said outer form toward said inside form.

ADOLF H. ALTVATER.
